William Borchert
By J. J. Wilson
Atty.

UNITED STATES PATENT OFFICE.

WILLIAM BORCHERT, OF ROCKFORD, ILLINOIS.

TAG.

1,412,998.

Specification of Letters Patent. Patented Apr. 18, 1922.

Application filed July 15, 1920. Serial No. 396,564.

To all whom it may concern:

Be it known that I, WILLIAM BORCHERT, a citizen of the United States, residing at Rockford, in the county of Winnebago and 5 State of Illinois, have invented certain new and useful Improvements in Tags, of which the following is a specification.

This invention pertains in general to tags adapted to take the impressions of marking 10 characters applied either by hand or machine and to be attached to articles or materials of various kinds for purpose of identification, or for any other reason, and has more particular reference to tags of this kind especially 15 adapted for use in laundries and similar places for identifying by a distinguishing mark placed on the tag, the ownership of an article of apparel, or any article to which the tag is attached.

20 The primary object of my invention is to provide a tag of the kind generally known as a staple tag, of generally improved construction and possessing various features of advantage to the user as will be more fully 25 pointed out hereinafter.

One of the important objects of my invention resides in the provision of a fabric body tag equipped with metallic fastening spurs, and so constructed that each edge of the fabric piece from which the body is made is turned in, in a particularly advantageous manner to prevent unravelling and fraying of the edges. This fraying very frequently occurs in the ordinary staple tags now on 30 the market when the garments and tags are passed through the various washing machines in a laundry, with the result that the fabric body becomes loosened from the staples and pulled out.

40 Another object is the provision of a novel fastening means which permits attachment of the mark-receiving body to a garment in a very substantial manner and obviates the danger of tags loosening and being lost in 45 the wash.

Still another important object is the arrangement of the metallic fastening means in such novel manner on the fabric tag body as to give a marking surface of maximum 50 length, and unlimited by reason of the presence of metallic spurs found on the face of other staple tags. In other words, I have so arranged the fastening staples as to allow an uninterrupted marking surface from 55 end to end of the fabric body, thus enabling the type characters to form impressions

throughout the length of the tag. In this regard, I have also aimed to arrange the metallic fastening staples and fabric body in such co-operative relation that said staples 60 will not be injurious to metallic type used in marking machines for marking these tags.

My invention also contemplates shaping the fabric body and pliable metal staples in such novel manner as to promote economy in 65 manufacture and secure various advantages to the user. The fabric body and spurs by reason of their peculiar construction, are so united that the spurs pass through a reinforced body and are thus so united to the 70 fabric body as to preclude tearing or displacement of the body from the staples after the tag has been attached to a garment. Furthermore, the fabric body is so constructed 75 that it cannot unravel or fray at the edges and presents with the auxiliary backing, a firm marking body, the surface of which extends from end to end of the tag, thus giving a maximum marking length for a tag of 80 its size.

Other objects and attendant advantages will be appreciated by those familiar with the art as the invention becomes better understood by reference to the following description when considered in connection 85 with the accompanying drawings, in which—

Figure 1 is a view of a fabric blank, forming a part of my improved tag;

Fig. 2, a view showing the end flaps turned in;

Fig. 3, a view showing the side flaps turned over the end flaps;

Fig. 4, a view of a staple blank;

Fig. 5, the blank bent to U-shape for piercing the fabric body;

Fig. 6, shows a staple pressed through the underside of a folded fabric body;

Fig. 7, an enlarged face view of one end of the tag with the spurs of the staple bent in operative holding position;

Fig. 8, a cross-sectional view taken on the line 8—8 of Fig. 7;

Fig. 9, a side view of the end of the tag shown in Fig. 7; and

Fig. 10, a face view of a complete tag, 105 marked.

While the tag herein illustrated has been particularly designed for laundry use in a well known manner, it should be understood that it is adapted for a wider range of use, that is, for attachment to other articles and materials than those customarily tagged in 110

a laundry. The tag is of the kind known as a staple tag, so designated because of the staple at each end for attaching it to a garment.

5 As a matter of explanation, it might be mentioned that the fabric blanks and the pliable metal staples which make up the present tag are blanked out and assembled by means of an automatic machine, that is, one 10 which performs the several blanking and assembling operations automatically. The fabric body which receives the marking impression is cut to the shape indicated in Fig. 1, from a strip of fabric. This strip of any 15 suitable length, is generally in a roll, and by feeding the strip through cutting dies it is cut off consecutively into blanks designated generally by the character 12. It will be noted that the corners of this rectangular 20 blank are cut away forming end and side flaps 13 and 14 respectively, the intermediate portion 15 constituting a major body portion for the reception of the marking impressions. It should be understood, of course, that this 25 blanking operation might be performed in any suitable manner. The first operation after blanking is to fold the end flaps 13 over the underside of the body 15 as shown in Fig. 2. The side flaps 14 are then folded 30 over the end flaps in the manner shown in Fig. 2, thus producing a rectangular fabric body, every edge of which is lapped to prevent fraying and unravelling. It will be further noted that the three-ply corners 35 afford a substantial reinforced body through which the staples are pierced for attaching the tag. By reason of this construction, the body has in itself, sufficient strength and material to obviate the necessity of an 40 auxiliary filling as is frequently used in other tags. The face 16 of the fabric body lying on top of the flaps 13 and 14 constitutes the marking surface, and as will be presently seen, this surface is available from end to 45 end for marking purposes, whereas, in other makes of staple tags the top face or marking surface is interrupted by metallic spurs, the position of which necessarily limit the length of the surface which may be marked.

50 Coming now to the fastening staples, by means of which the fabric bodies are respectively attached to a garment or piece of material, it should be noted that my invention contemplates associating these staples 55 with the fabric body in such novel manner as to prevent both the staples from pulling away from the garment and the fabric body from the staples under the exigencies of usage and to allow the full length marking 60 surface mentioned above. A staple blank in its preferred shape is shown in Fig. 4 and should be cut from pliable non-rustable sheet metal. It will be observed that the staple blank is shaped to provide a medial body 65 portion or shank 17, pointed spurs 18 on

diagonally opposite corners and double shoulders 19 and 21 at the neck of the spurs. These metal blanks are bent at their corners 19 to U-shape, as shown in Fig. 5. One of these staples is then driven through each 70 end of the fabric body from the underside thereof as shown in Fig. 6, so that the spurs pass through the three-ply body at each corner thereof. Assuming now that a tag equipped with staples as shown in Fig. 6, is 75 inverted, the spurs 18 will project up from the mark-receiving face 16 as indicated in dotted lines in Fig. 8. These spurs are now turned outwardly and downwardly at right angles to the plane of the marking face in 80 the manner shown in full lines in said figure. A tag thus assembled is complete and ready for attachment to a garment or any suitable piece of material. The downwardly projecting spurs 18 may be pressed through the 85 material and then turned inwardly into overlapping relation as indicated by dotted lines in Fig. 7, the pointed ends of the spurs being pressed upwardly toward and embedded in the body of the garment so as to retain its 90 clinched or holding position and prevent scratching. A tag may be thus attached to a piece of material either by hand or by means of a suitable tag-affixing device.

Attention is directed to Fig. 10, which 95 shows a face view of my improved tag, marked "National" from which it will be noted that the marking face of the tag is uninterrupted from end to end, thus permitting a maximum number of type characters to be used on a tag of a given length. This result is due to the novel arrangement of the fastening staples which neither pierce nor extend over the mark-receiving area of the tag. Instead, however, the shank portion 17 of each staple is arranged beneath the fabric mark-receiving surface and only that portion of the staple between the shoulders 19 and 21 appears above the marking surface. These shoulders 19 and 21 facilitate accurate bending of the staple at the requisite points. It will be especially noted that three thicknesses of fabric cover the shank portion 17 and thus insure ample protection against marring the metallic type 110 used in a marking machine. In other words, these tags may be marked from end to end by a mechanical marking machine without injury to the type characters thereof. By reason of my improvements, a maximum 115 marking surface is available with a tag of given size, consequently a tag for the reception of a maximum number of characters ordinarily used may be made much smaller, produced more economically and 120 shipped in less bulky packages than other tags for the same purpose. The staples further function in holding the overlapped edges securely in their proper position, it being noted that the fabric is held by double 125 130

bends of the staples. Viewing Fig. 6, it will be manifest that a staple in piercing the corners in the manner shown and by reason of its shank portion 17 traversing the 5 side flaps 14, holds these parts against displacement and upon bending the spurs 18 outwardly through about 180 degrees to the position shown in Fig. 8, the staple effectively locks the fabric flaps in position. It 10 will be further noted that all of the edges of the finished tag are folded, thus precluding unravelling and fraying and further providing a multiply fabric body with the warp and weft threads of one ply trans- 15 verse to those of another so as to effect a very substantial construction preventing the fabric tag from pulling away from the staples. And by reason of the peculiar shape the staples and their arrangement 20 on the fabric body, the spurs when finally bent in for securing a tag to a garment do not interfere and cause one spur to project unsheathed, a source of danger to the wearer. Instead, special provision has been 25 made for ample clearance between the spurs so that when they are folded down either by hand, machine or otherwise, a compact arrangement is secured and the spur points may be each pressed into the fabric of the 30 garment, and thus rendered harmless.

It is believed that the foregoing conveys a clear understanding of the principles and objects of my invention, and while I have illustrated in the drawing but a single 35 working embodiment thereof, it should be understood that various changes might be made in the construction and arrangement without departing from the spirit and scope of the invention as expressed in the ap- 40 pended claims: in which—

I claim:

1. A tag of the character described com-

prising a rectangular strip of fabric cut away at each corner to provide end and side flaps and an intermediate body portion, 45 said flaps being folded over said body portion to provide a reduced rectangular tag body, the corners of which are reinforced, and metallic spurs piercing said corners and adapted to secure the tag to a piece of ma- 50 terial.

2. A tag of the character described comprising a rectangular strip of fabric cut way at each corner to provide end and side flaps and an intermediate body portion, said 55 ends being folded under said body portion and the sides folded under the ends and said body portion, and a substantially U-shaped staple for each end of the tag so associated therewith as to pierce each reinforced corner and present fastening spurs depending from the underside of the mark-receiving body.

3. A tag of the character described, comprising a rectangular fabric body, the corners of which are cut away forming end flaps and side flaps, and an intermediate portion adapted for the reception of marking impressions, said side and end flaps being turned in under said mark-receiving portion, and means passing through the three-ply corners of the tag for securing said flaps in co-operative relation with the mark-receiving portion of the tag.

4. A staple tag comprising a fabric mark-receiving body having its ends and sides folded under, and a metallic staple for fastening each end of the fabric body to a piece of material, each staple having fastening spurs piercing the multi-ply corners 80 of the body and having its medial portion extending across the folded under sides for holding them against displacement.

WILLIAM BORCHERT.
